UNITED STATES PATENT OFFICE.

DOCK GLEN HORTON, OF BIRMINGHAM, ALABAMA.

SHADE-ROLLER.

1,352,410.

Specification of Letters Patent. Patented Sept. 7, 1920.

Application filed August 28, 1919. Serial No. 320,351.

To all whom it may concern:

Be it known that I, DOCK G. HORTON, a citizen of the United States, residing at Birmingham, in the county of Jefferson and State of Alabama, have invented certain new and useful Improvements in Shade-Rollers; and I do declare the following to be a full, clear, and exact description of the invention, such as will enable others skilled in the art to which it appertains to make and use the same.

My invention relates to spring wound rollers for window shades and has for one object to provide a novel substitute for the usual ratchet mechanism thereof, so constructed as to arrest rapid winding of the roller in case it is accidentally released, thereby preventing the shade from being entirely rolled up as now often occurs.

20 A further object is to provide a simple, inexpensive, durable and reliable sheet metal roller having novel construction for holding several of the interior working parts in place, as well as the shade.

25 With the foregoing in view the invention resides in the novel construction and arrangement of parts hereinafter fully described and claimed, the descriptive matter being supplemented by the accompanying drawing which forms a part of this application.

Figure 1 is a longitudinal section of a shade roller constructed in accordance with my invention.

35 Figs. 2 and 3 are transverse sections on the planes of lines 2—2 and 3—3 of Fig. 1.

Fig. 4 is a perspective view of the non-rotating pintle and the head carried thereby.

Fig. 5 is a plan view of part of the metal blank from which the roller is constructed.

In the drawing above briefly described, the numeral 1 designates the preferably sheet metal shell of the roller, the ends of said shell being crimped at 2 around the edges of two end members 3 and 4, said member 3 having an opening 5 while the member 4 carries the cylindrical pintle 6 of the roller. The non-rotating or flat pintle 7 is rounded at its inner end as seen

50 at 8 and is received in the opening 5, said pintle extending from a head 9 having a notch 10 in its periphery receiving a ball 11 which travels on an annular brake surface within the roller, said surface being preferably formed by the inner side of an

annular flange 12 which extends from the end member 3.

The notch 10 is provided with an inclined side 13 which converges with respect to the flange or brake surface 12, and the ball 11, 60 although being of such size as to roll freely on said flange or surface when the shade is being wound or unwound, either slowly or rapidly, is sufficiently large to wedge between the sides 13 and said flange or surface, if the shade roller quickly moves in shade-winding direction. Thus, when the shade has been raised or lowered to the proper extent, a sudden upward movement thereof will dispose the ball to active position so as to hold the roller against further movement until required. Should the shade be accidentally released, the sudden quick movement of the roller will throw the ball 11 to locking position and thus the roller 70 cannot entirely wind the shade thereon as now often occurs with the common types of rollers.

The usual spring 14 is positioned in the roller and at 15 is passed through an opening in head 9 and seated in a groove 15', while the other end of said spring has a suitable connection with the roller. In the present showing, this spring is attached at 16 to a disk 17 in the shell 1, said disk having a peripheral notch 18 receiving an internal rib 19 which extends longitudinally of said shell. The rib 19 is formed at the meeting edges of the metal sheet of which the shell is constructed, and said edges may 80 well overlap for a part of their length as seen in Fig. 2 to form an anchorage for the upper end of the shade 20. A rod 21 passes longitudinally through the spring 14 to prevent bowing of the latter, one end of said 85 rod fitting into a socket 22 in the head 9 while the other end passes loosely through a central opening in the disk 17, the latter being held in place by a cotter pin or the like 23. The rod 21 is provided with a lateral flange 24 which retains the ball 11 in the notch 10, and said flange may well be formed by a washer held in place by the spring 14.

When the shade is pulled downwardly, all 105 parts rotate except the pintle 7, the head 9, the rod 21, and one end of the spring 14. This spring is thus wound to rotate the roller in a direction to wind the shade thereon whenever required, and after raising or 110

lowering said shade to the proper extent, the ball 11, the side 13, and the brake surface 12, come into play to hold the shade in adjusted position. When raising or lowering the shade, should it be accidentally released, or should such release take place after the shade has been properly positioned, it is prevented from totally winding up, by its rapid movement shifting the ball 11 to locking position.

The device may be constructed easily and inexpensively, yet will be highly efficient and in every way desirable and since probably the best results can be obtained from the details disclosed, they may well be followed. I wish it understood, however, that within the scope of the invention as claimed, numerous minor changes may well be made.

I claim:

20 1. A hollow spring-wound shade roller having an annular internal brake surface at one end, a non-rotating stub shaft passing centrally into said end of the roller and having a head surrounded by said annular 25 brake surface, the periphery of said head having a notch in its lower side provided with a side wall in converging relation with said brake surface, and a ball supported by said brake surface and positioned in said 30 notch for coaction with said wall and said brake surface to hold the roller in adjusted position and to prevent rapid winding thereof.

2. A hollow spring-wound shade roller 35 having an annular internal brake surface at one end, a non-rotating stub shaft passing centrally into said end of the roller and having a head surrounded by said annular brake surface, the periphery of said head 40 having a notch provided with a side wall in converging relation with said brake surface, a ball in said notch for coaction with said wall and said brake surface to hold the roller in adjusted position and to prevent 45 rapid winding thereof, a coiled spring in said casing connected at one end with said roller and at its other end with said head, a rod extending from said head through said spring, and a lateral flange on said rod 50 for retaining said ball in said notch.

3. A shade roller comprising a tubular shell, end members secured to the ends of said shell, one of said end members having a cylindrical pintle and the other having a central opening, an annular flange extending inwardly from said last mentioned end member concentric with said opening, a non-rotating pintle passing through said opening and having a head surrounded by said flange, the peripheral edge of said head having a notch in its lower side provided with a side wall disposed in converging relation with said flange, a ball supported by said flange and disposed in said notch and coacting with said wall and said flange to hold the roller in adjusted position, and a spring in said shell connected at one end with said head and connected at its other end with said shell.

4. A hollow spring-wound curtain roller 70 consisting of circular end members, a metal shell crimped at its ends around the edges of said end members, one of said end members carrying a cylindrical pintle and the other having an opening, a non-rotating pintle 75 passing loosely through said opening, a spring in said shell connected at one end with the latter and at its other end with said non-rotating pintle, and means for holding the roller in adjusted position. 80

5. A shade roller comprising two end members, one of said members carrying a cylindrical pintle and the other having an opening, a single sheet of metal bent into tubular form with its ends secured to the edges of said end members, the edges of said metal sheet being overlapped and stamped inwardly to provide an internal rib and to form anchoring means for the upper end of the shade, a non-rotating pintle passing loosely through the aforesaid opening, a spring in said shell connected at one end to said non-rotating pintle, a disk in said shell attached to the other end of the spring and having a peripheral notch receiving said 95 rib, and means for holding the roller in adjusted position.

In testimony whereof I have hereunto set my hand.

DOCK GLEN HORTON.
